UNITED STATES PATENT OFFICE.

CHARLES M. YATES, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CONDENSER.

1,239,067.

Specification of Letters Patent.

Patented Sept. 4, 1917.

Application filed December 24, 1915. Serial No. 68,934.

To all whom it may concern:

Be it known that I, CHARLES M. YATES, a citizen of the United States, residing at Milwaukee, in the county of Milwaukee and 5 State of Wisconsin, have invented a certain new and useful Improvement in Condensers, of which the following is a specification.

This invention relates to improvements in the construction of steam condensers, and 10 particularly to improvements in jet condensers of the high vacuum type.

An object of the invention is to provide a condenser which is simple in construction and efficient in operation. One of the more 15 specific objects of the invention is to provide a jet condenser of the high vacuum type in which the injection water is uniformly distributed in the condenser zone to produce rapid and effective condensation of 20 the steam. Another object is to provide an efficient jet condenser of large capacity in which the injection water is effectively delivered into and distributed in the condensing zone by gravity. A further object is to 25 provide means for effectively injecting cooling water into all portions of the condensing zone of relatively large jet condensers. A further object is to provide a high vacuum 30 jet condenser which will retain maximum efficiency throughout a considerable range of operating conditions.

A clear conception of an embodiment of the invention may be had by referring to the drawing accompanying and forming a 35 part of this specification in which like reference characters designate the same or similar parts in the various views.

Figure 1 is a fragmentary transverse vertical section through a jet condenser having 40 the invention applied thereto.

Fig. 2 is a top view of the inner casing which forms the condensing zone of the condenser.

The condenser comprises essentially a vertical cylindrical outer casing 6 having a steam inlet 1 at the upper end thereof, a water inlet 2 at the side thereof near the top of the outer casing, an air outlet 3 somewhat below the water inlet 2, and a water outlet, 45 not shown, near the lower end of the casing. While the casing 6 is disclosed as comprising several detachable sections, this construction is not essential. The inner casing 50

5 comprises a perforated annular upper wall forming a condensing zone and having 55 a downwardly extending constricted portion forming an outlet 4 leading from the condensing zone. The mid portion of the casing 5 is provided with an outwardly extending flange which is secured to an annular wall 15 the lower extremity of which 60 engages an upper surface of the casing 6 and provides a support for the inner casing 5. The annular wall 15 besides forming a support for the casing 5, forms a water distributing pocket surrounding the lower portion 65 of the perforated upper end of the casing 5.

The annular upper wall of the casing 5 is provided with several circular series of 70 perforations or orifices 12, 13, 14, arranged one above the other and opening directly into the condensing zone. The orifices 12 of the upper series open into inwardly extending troughs 42, which are secured to the 75 casing 5 and have their inner ends opening toward the center of the condenser. The orifices 12 of the upper series may be made larger and fewer in number than those of the intermediate series 13, while the orifices 80 13 of the intermediate series may be made larger and fewer in number than the orifices 14 of the lowermost series. The orifices of the adjacent series are preferably arranged out of vertical alinement with each other, 85 thus giving them a staggered relation to each other. The upper extremity of the perforated annular wall 5 is provided with a series of inwardly extending open troughs 11, which in the present disclosure are arranged substantially radially. Each of the troughs 11, 42, is provided with perforations or orifices 18, 19, respectively, opening directly into the condensing zone. The troughs 11 of the upper series are preferably 90 arranged out of vertical alinement with the troughs 42 of the lower series. The orifices 12, 13, 14, and troughs 11 are preferably made of such size and number that each series will tend to deliver substantially the 95 same amount of cooling water to the condensing zone that an adjacent series delivers.

The central portions of the condensing zone is provided with a vertical casing 9 having superposed series of orifices 20 opening directly into the condensing zone. The 105

openings 20 are so arranged that they will inject water into the condensing zone away from the center thereof. The openings 20 of successive series are preferably arranged 5 out of vertical alinement, thus giving them a staggered relation to each other. The casing 9 is supported from the wall 15 and casing 5 by means of pipes 8 which also serve to admit injection water to the interior 10 of the casing 9 from the water inlet 2.

The steam inlet 1 of the casing 6 is arranged in line with the upper portion of the casing 5 and also serves as an inlet to the condensing zone. The water inlet 2 connects 15 with an annular passage 22 which surrounds the annular wall 15. The annular baffle wall 16 extends downwardly from the cover of the casing 6 and forms an annular air pocket 23 at the extreme upper end of 20 the condenser. The constricted lower portion of the casing 5 which forms the outlet 4, projects downwardly into the collection chamber at the bottom of the casing 6 to a point adjacent the air inlet 3. The casing 25 6 and constricted outlet portion of the casing 5 coact to form an annular air pocket 10 for non-condensable vapors, which communicates directly with the air outlet 3. The lower central portion of the outlet 4 30 is provided with a hood 7 supported from the lower constricted portion of the casing 5, the interior of which connects directly with the pocket 10 through the pipe 21. The air pocket 10 is connected with the air 35 pocket 23 at the upper end of the condenser by means of a series of pipes 17.

During the normal operation of the device, the exhaust steam flowing at high velocity is admitted to the condensing zone 40 within the casing 5 through the steam inlet 1. The injection water admitted through the water inlet 2 flows around the annular distributing passage 22 and into the space directly adjacent the perforated wall of the 45 casing 5. As the injection water flows through the orifices 12, 13, 14, and the troughs 11, 42, it is delivered by gravity into the condensing zone and toward the center thereof in the form of streams.

50 Some of the water entering the troughs 11, 42, is precipitated longitudinally into the condensing zone through the orifices 18, 19, while the remainder of the water passing through these troughs is delivered over 55 the inner ends thereof to points near the center of the condensing zone. A portion of the water admitted into the distributing passage 22 passes through the pipes 8 into the interior of the casing 9, from which it 60 is delivered through the orifices 20 in the form of streams directed away from the center of the condensing zone. As the steam admitted through the inlet 1 passes downwardly through the condensing zone, 65 it is compelled, due to the staggered ar-

angement of the troughs 11, 42, and the orifices 12, 13, 14, 20, to take a circuitous path between the streams flowing from these orifices and troughs. Due to the great number and the staggered relation of the streams 70 of water admitted to the condensing zone, the steam is quickly condensed and the mixture of water and non-condensable vapors is delivered to the chamber at the lower end of the casing 6, through the outlet 4. The 75 mixture of water and non-condensable vapor thus delivered to the lower portion of the casing 6 is discharged from this casing in the usual manner. Some of the non-condensable vapors escaping from the mixture 80 rise into the hood 7 and pocket 10, from which they are withdrawn through the air outlet 3.

The provision of the walls 15, 16, insures 85 perfect distribution of the injection water to all portions of the condensing zone and prevents local injection of a greater portion of the water to one side of the condensing zone. The air pipes 17 and the pipe 21 permit ready withdrawal by the air pump 90 of any vapors which may gather in the pocket 23 and the hood 7. The portion of the casing 5 which forms the outlet 4 is preferably so formed that the streams of water delivered through the lower orifices 9 14, substantially follow the contour of this portion of the casing. On account of the difference in head of the water delivered to the troughs 11, 42, and the orifices 13, 14, respectively, it will be noted that the streams 100 delivered through the lower orifices 14 will tend to pass inwardly to a greater extent than those delivered from the upper orifices. In order to prevent excessive inward travel 105 of the lowermost streams, the lower portion of the perforated wall of the casing 5 is formed downwardly diverging.

In order to prevent the formation of a dead space in condensers of relatively large size in which non-condensable vapors might 110 collect and into which no injection water is projected, the central perforated casing 9 is provided. While the troughs 11, 42, tend to eliminate the formation of such a dead space, the casing 9 and orifices 20 will positively prevent its formation. The streams 115 of water delivered from the orifices 18, 19, 20, coöperate with the streams delivered from the ends of the troughs and from the lower orifices 13, 14, and produce a maximum 120 amount of cooling water surface.

It is desirable in the operation of the condenser to have the injection water flow 125 through the orifices and troughs under the impelling influence of gravity and hydrostatic head only, and with the condenser operating at full load to have substantially the same quantity of cooling water entering the condensing zone through each series of orifices in the casing 5. These results are at- 130

tained by the use of the present invention. While the troughs 11, 42, have been disclosed as formed integral with the casing 5, such construction is not essential.

5 It should be understood that it is not desired to be limited to the exact details of construction shown and described, for obvious modifications will occur to a person skilled in the art.

10 It is claimed and desired to secure by Letters Patent,—

1. In combination, a casing forming a condensing zone, means for injecting water horizontally into said zone toward the center thereof, means for injecting water horizontally into said zone away from the center thereof, a steam inlet to said zone, and an outlet from said zone.

2. In combination, a casing forming a condensing zone and having orifices opening horizontally into one portion of said zone, a second casing having orifices opening horizontally into another portion of said zone, means for injecting water into said zone through said orifices, a steam inlet leading to said zone, and an outlet from said zone.

3. In combination, a casing forming a condensing zone and having orifices opening into one portion of said zone, a plurality of troughs having orifices opening into another portion of said zone, a second casing having orifices opening into another portion of said zone, means for injecting water into said zone through said orifices, a steam inlet leading to said zone, and an outlet from said zone.

4. In combination, a vertical casing forming a condensing zone, means for injecting water horizontally into said zone toward the center thereof, means for injecting water horizontally into said zone away from the center thereof, means for injecting water into said zone longitudinally thereof, a steam inlet to said zone, and an outlet from said zone.

5. In combination, a vertical cylindrical casing forming a condensing zone, means for injecting streams of water radially and horizontally into said zone toward the center thereof, means for injecting streams of water radially and horizontally into said zone away from the center thereof, a steam

inlet adjacent the upper end of said casing, and an outlet adjacent the lower end of said casing.

6. In combination, means forming an annular condensing zone free from structural elements, means for injecting water into said zone toward the axis of annularity, means for injecting water into said zone away from said axis, a steam inlet into said zone, and an outlet from said zone.

7. In combination, means forming a vertical annular condensing zone free from structural elements, means for injecting horizontal streams of water into said zone toward the axis of annularity, means for injecting horizontal streams of water into said zone away from said axis, a steam inlet adjacent the upper end of said zone, and an outlet adjacent the lower end of said zone.

8. In combination, means forming an annular condensing zone and having oppositely directed orifices opening into said zone, a plurality of troughs having orifices opening into said zone, means for injecting water into said zone through said orifices, a steam inlet leading to said zone, and an outlet from said zone.

9. In combination, means forming an annular condensing zone and having oppositely directed orifices opening into said zone transversely of the axis of annularity, means having orifices opening into said zone in the direction of said axis, means for injecting water into said zone through said orifices, a steam inlet leading to said zone, and an outlet from said zone.

10. In combination, a casing forming a vertical annular condensing zone and having radial oppositely directed orifices opening into said zone, a plurality of troughs having orifices opening into said zone, means for injecting water into said zone through said orifices, a steam inlet adjacent the upper end of said casing, and an outlet adjacent the lower end of said casing.

In testimony whereof, the signature of the inventor is affixed hereto.

CHARLES M. YATES.
